RECLINING ARTICLE OF FURNITURE

Anton Lorenz, Buffalo, N. Y.

Application September 17, 1946, Serial No. 697,503

5 Claims. (Cl. 155—105)

1

This invention relates to articles of furniture, and more particularly to a reclining article of furniture, wherein the seat and a downward extension of the back-rest form movable links of a polygonal compound linkage swingably mounted on a support, a portion of the latter forming the stationary link of said linkage.

An object of the present invention is to provide a reclining article of furniture of above described type, wherein the movable members of the article of furniture are very well balanced, so that an occupant resting in the article of furniture may bring the movable members of the article of furniture from one position into another position without great effort.

A further object of the present invention is to provide a reclining article of furniture of above described type equipped with a leg-rest swingably mounted on the seat and controlled by a controlling mechanism, wherein the leg-rest may be swung through a relatively large angle during a movement of the movable members of the article of furniture from their sitting position into their extreme reclined position.

Still another object of the invention is to improve upon reclining articles of furniture as currently made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side-elevational view of an adjustable reclining chair according to the invention, a portion of a side wall being broken away.

Fig. 2 is a sectional view taken on line 2—2 of Fig. 1, and

Fig. 3 is an elevational view of another embodiment of an adjustable reclining chair in accordance with the invention, a portion of the support being broken away.

Referring now to Fig. 1, 10 generally indicates a support of a reclining chair. Said support comprises two side frames 12 and 14 which are connected to each other by a plurality of cross-bars 16.

The rear portion of a seat 18 is pivoted to said support 10 at 20. On each side of the chair the front portion of said seat 18 is pivotally connected at 22 with the upper portion of a front link 24. Said front link 24 is pivotally connected at 26 at a point below the pivotal connection 22 between the

2

front link 24 and the seat 18 with the lower end portion of a connecting link 28, the upper end portion of which is pivoted to the support 10 at 30 at a point spaced from the pivotal connection 20 between the seat 18 and the support 10. Thus, the movable seat 18, the movable front link 24, the movable connecting link 28 and the stationary portion of the support 10 between the pivotal connection 30 of the connecting link 28 with said support and the pivotal connection 20 of the seat 18 with said support form the links of a four-bar link-mechanism.

A back-rest 32 is pivoted to the support 10 at 34 at a point spaced from the pivotal connection 20 between the seat 18 and the support 10. Said back-rest 32 has a downward extension 36 projecting downwardly beyond the pivotal connection 34 between the back-rest 32 and the support 10. According to the embodiment shown in Fig. 1, said extension 36 is integral with the back-rest 32; said extension, however, could also be made of a separate piece of material rigidly connected with said back-rest 32 in any suitable manner. On each side of the chair, the rear portion of a lower link 38 is pivoted to said extension 36 of the back-rest 32 at a point 40 below the pivotal connection 34 between the back-rest 32 and the support 10. The front link 24 has an extension 42 projecting beyond its pivotal connection 26 with the connecting link 28. The front portion of the lower link 38 is pivoted at 44 to said extension 42 of the front link 24 at a point spaced from the pivotal connection 26 of said front link 24 with the connecting link 28.

Above described four-bar link-mechanism 18, 24, 28, 30—20 and the link-chain 36, 38 form in combination with each other a polygonal compound linkage. The links of said polygonal compound linkage may be readily arranged in such a manner and in such proportions, that the movable members of the chair are very well balanced, so that an occupant resting in the chair may bring the movable members of the chair from one position (for example the sitting position shown in full lines) into another position (for example the extreme reclined position shown in dash-and-dot lines) without great effort.

Furthermore, the leg-rest 46 is swingably mounted on the front portion of the seat 18 at 48. One end of a controlling link 50 is pivotally connected with said leg-rest 46 at 52, the other end of said controlling link 50 is pivotally connected with an extension 53 of the connecting link 28 at 56. Said controlling link 50 serves to control the swinging movements of the leg-rest 46 about its

pivot 48 when the movable members of the chair are moved from one position, for example the sitting position shown in full lines, into another position, for example the extreme reclined position shown in dash-and-dot lines.

The sitting position of the movable members of the chair is limited by a stop 56 mounted on the support 10 for abutting engagement with the extension 36 of the back-rest 32. The extreme reclined position of the movable members of the chair is limited by a stop 58 mounted on the support 10 for cooperation with the back-rest 32.

When the occupant of the chair leans the weight of his body against the back-rest 32, the latter will be swung from its upright position shown in full lines into a reclined position shown in dash-and-dot lines. At the same time, the seat 18 and the leg-rest 46 will be lifted into the dash-and-dot lines positions through the medium of above described linkage and controlling means.

The movable members of the chair may be held in any desired position, for example in the extreme reclined position shown in dash-and-dot lines or in any other intermediate reclined position, by means of a locking device generally indicated by 60. As best shown in Figs. 1 and 2, said locking device 60 comprises a locking rod 62 pivoted to the seat 18 at 64 and slidably engaged with a clip 66. A supporting element 68 is secured to the side-frame 12. A bolt 70 having a head 72 at one of its ends and having a threaded portion 74 at its other end passes through a bore 76 of the supporting element 68, through the bore 78 of a washer 80 interposed between the supporting element 68 and the clip 66, through the bores 82 of the clip 66 and through the bore 84 of a sleeve 86 slidably arranged in a bore 88 of the side frame 12 and interposed between the clip 66 and a locking knob 90 screwed on the threaded end portion of the bolt 70. A nose 92 arranged on the 78 and engaged with a recess of the supporting element 68 prevents the bolt 70 from rotation. When the locking knob 90 is loosened, the locking rod 62 may freely slide in the clip 66, and, consequently, the movable members of the chair may freely be moved from one position into another one. When the locking knob 90 is tightened, the sleeve 86 is urged against the clip 66, whereby said clip is tightened on the locking rod 62, so that the members of the chair are held in their position. Of course, any other type of locking device may be used instead of said locking device 60, if desired.

According to the embodiment of an adjustable reclining chair shown in Fig. 3, the support 110 is made of tubular material bent in a suitable manner so as to form the side-frames 112 and 114. Again, the movable seat 118 pivoted to the support 110 at 120, the movable front link 124 pivoted to the seat 118 at 122, the movable connecting link 128 pivoted to the front link 124 at 126 and pivoted to the support 110 at 130 as well as the stationary portion of the support 110 between the pivots 130 and 120 form the links of a four-bar link-mechanism. Furthermore, again the back-rest 132 having a downward extension 136 is pivoted to the support 110 at 134 at a point spaced from the pivotal connection 120 between the seat 118 and the support 110. Moreover, the rear portion of the lower link 138 is pivoted to the extension 136 of the back-rest 132 at 140. According to Fig. 3, however, the front portion of said lower link 138 is pivoted at 144 to an intermediate point of the front link 124 between the

pivotal connection 122 of the front link 124 with the seat 118 and the pivotal connection 126 of the front link 124 with the connecting link 128.

The sitting position of the movable members of the chair shown in full lines is limited by the stop 156 mounted on the support 110 for cooperation with the extension 136 of the back-rest 132. The extreme reclined position of the movable members of the chair is limited by the stop 158 mounted on the support 110 for cooperation with the back-rest 132.

When the back-rest 132 is swung from its upright position into the reclined position shown in dash-and-dot lines, the seat 118 is lifted into the reclined position shown in dash-and-dot lines through the medium of above described linkage.

The movable members of the chair may be held in any desired position by means of the locking device 160 arranged on a lug of the frame and substantially corresponding to the locking device shown in Fig. 2.

I have described preferred embodiments of my invention, but it is understood that this disclosure is for the purpose of illustration, and that various omissions or changes in shape, proportion, and arrangement of parts, as well as the substitution of equivalent elements for those, herein shown and described, may be made without departing from the spirit and scope of the invention as set forth in the appended claims.

For example, one or more of the links of the linkage of the chairs may be in the shape of a bent link instead of a straight link as shown in the drawings.

Furthermore, one or more of the links of the linkage of the chairs may be made of adjustable length so as to vary the relative positions and movements of the members of the chair.

Furthermore, the invention may be applied to other articles of furniture than the type of chairs shown in the drawings, for example to office chairs, garden chairs, chairs for use in railroad cars, chairs for use in airplanes, lounges, etc.

What I claim is:

1. A reclining article of furniture, comprising: a support, a seat, the rear portion of said seat being pivoted to said support, a front link, the upper portion of said front link being pivoted to the front portion of said seat, a connecting link, one end portion of said connecting link being pivoted to said front link at a point below the pivotal connection between the front link and the seat, the other end portion of said connecting link being pivoted to said support at a point spaced from the pivotal connection between the seat and the support, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from the pivotal connection between the seat and the support, said back-rest having an extension projecting downwardly beyond the pivotal connection between said back-rest and said support, and a lower link, the rear portion of said lower link being pivoted to said extension of the back-rest below the pivotal connection between the back-rest and the support, and the front portion of said lower link being pivoted to a point of the front link spaced from its pivotal connection with the connecting link.

2. A reclining article of furniture, comprising: a support, a seat, the rear portion of said seat being pivoted to said support, a front link, the upper

portion of said front link being pivoted to the front portion of said seat, a connecting link, one end portion of said connecting link being pivoted to said front link at a point below the pivotal connection between the front link and the seat, the other end portion of said connecting link being pivoted to said support at a point spaced from the pivotal connection between the seat and the support, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from the pivotal connection between the seat and the support, said back-rest having an extension projecting downwardly beyond the pivotal connection between said back-rest and said support, a lower link, the rear portion of said lower link being pivoted to said extension of the back-rest below the pivotal connection between the back-rest and the support, the front portion of said lower link being pivoted to a point of the front link spaced from its pivotal connection with the connecting link, and locking means associated with at least one member of the link-system of the article for locking the movable members thereof.

3. A reclining article of furniture, comprising: a support, a seat, the rear portion of said seat being pivoted to said support, a front link, the upper portion of said front link being pivoted to the front portion of said seat, a connecting link, one end portion of said connecting link being pivoted to said front link at a point below the pivotal connection between the front link and the seat, the other end portion of said connecting link being pivoted to said support at a point spaced from the pivotal connection between the seat and the support, said seat, said front link, said connecting link and the stationary portion of the support between the pivotal connections of the connecting link with the support and of the seat with the support forming the links of a four-bar link-mechanism, said front link having an extension projecting beyond its pivotal connection with the connecting link, a back-rest, said back-rest being pivoted to said support at a point spaced from the pivotal connection between the seat and the support, said back-rest having an extension projecting downwardly beyond the pivotal connection between said back-rest and said support, and a lower link, the rear portion of said lower link being pivoted to said extension of the back-rest below the pivotal connection between the back-rest and the support, and the front portion of said lower link being pivoted to said extension of the front link.

4. A reclining article of furniture, comprising: a support, a seat, the rear portion of said seat being pivoted to said support, a front link, the upper portion of said front link being pivoted to the front portion of said seat, a connecting link, one end portion of said connecting link being pivoted to said front link at a point below the pivotal connection between the front link and the seat, the other end portion of said connecting link being

5 pivoted to said support at a point spaced from the pivotal connection between the seat and the support, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from the pivotal connection between the seat and the support, said back-rest having an extension projecting downwardly beyond the pivotal connection between said back-rest and said support, and a lower link, 10 the rear portion of said lower link being pivoted to said extension of the back-rest below the pivotal connection between the back-rest and the support, and the front portion of said lower link being pivoted to an intermediate point of the front link between the pivotal connections of the 15 latter with the connecting link and the seat.

20 5. A reclining article of furniture, comprising:
a support, a seat, the rear portion of said seat
being pivoted to said support, a front link, the
upper portion of said front link being pivoted to
the front portion of said seat, a connecting link,
25 one end portion of said connecting link being
pivoted to said front link at a point below the piv-
otal connection between the front link and the
seat, the other end portion of said connecting link
being pivoted to said support at a point spaced
30 from the pivotal connection between the seat and
the support, said seat, said front link, said con-
necting link and the stationary portion of the sup-
port between the pivotal connections of the con-
necting link with the support and of the seat with
35 the support forming the links of a four-bar link-
mechanism, a back-rest, said back-rest being piv-
oted to said support at a point spaced from the
pivotal connection between the seat and the sup-
port, said back-rest having an extension project-
40 ing downwardly beyond the pivotal connection be-
tween said back-rest and said support, a lower
link, the rear portion of said lower link being piv-
oted to said extension of the back-rest below the
45 pivotal connection between the back-rest and the
support, the front portion of said lower link be-
ing pivoted to a point of the front link spaced
from its pivotal connection with the connecting
link, a leg-rest swingably mounted on the front
50 portion of said seat, and controlling means on a
member of said article for controlling movements
of the leg-rest, said member being exclusive of
the seat.

ANTON LORENZ.
